IRONER SHOE AND TABLE

Walter C. Erler, South Bend, Ind., assignor to
 Bendix Home Appliances, Inc., South Bend,
 Ind., a corporation of Delaware

Application September 26, 1947, Serial No. 776,224

1 Claim. (Cl. 219—19)

1

This invention relates to a shoe and table combination for an ironing machine of the type employing a rotatable padded roll with a metallic shoe adapted to contact the roll to iron articles fed between the shoe and roll from a table adjacent one edge of the shoe.

It is a primary object of the invention to provide a type of construction for a shoe and table combination which provides for connections between the shoe and table for supporting the shoe together with connections for operating thermostatic elements visible above the table and operable to adjust thermostatic units under the shoe.

It is a further object to provide proper insulation for heating elements under the shoe with a suitable shielding member over the insulation and extending under the shoe and table to provide a suitable combination unit capable of ironing and guiding articles.

The above and other objects of the invention will appear more fully from the following more detailed description and by reference to the accompanying drawings forming a part hereof and wherein:

Figure 1 is an end view of the shoe and table partly in section showing the general arrangement of the shoe and the connection between the thermostatic control and the adjustment thereof required underneath the table.

Figure 2 is a top view of the table and shoe combination showing the general arrangement.

Figure 3 is a bottom view of the shoe and table with portions of the insulating unit and the second cover removed to show the interior arrangement and also the means for adjusting the position of the table relative to the shoe.

Figure 4 is a view of the shoe and table partially diagrammatic showing the arrangement of the heating coils and the wiring diagram therefor.

Figure 5 is a section taken on the line 5—5 of Figure 3.

Figure 6 is a section taken on the line 6—6 of Figure 3.

Figure 7 is a section taken on the line 7—7 of Figure 3.

Figure 8 is an end view of an ironing machine of the type employing a shoe and table combination showing the relationship of these parts to the other parts of the ironing machine including the roll.

Figure 9 is a front view of the ironing machine showing the same relationships as in Figure 8.

Figure 10 is a view taken on the line 1A of Figure 1.

2

Figure 11 is a view taken on the line 1B of Figure 1.

Referring to the drawings, a metallic shoe 10 has an upper curved heating surface 11 and under the heating surface a grooved surface 12 carrying electrical resistive heating elements 13 and 14. The heating elements 13 and 14 are on separate circuits making a complete and separate loop for each half of the ironing shoe 10. The 10 loop 13 as shown in Figure 4 makes a complete loop around one-half of the shoe and the heating element 14 makes another separate loop around the other half of the shoe. Connected in series with each loop are thermostatic elements 15 and 16. These thermostatic elements are in effect thermostatic switches which may be manually adjusted and set to break contact in the electrical circuit at a certain pre-determined temperature. The temperature at which such contact will be 20 broken may be varied by rotation of a shaft 17 of the thermostat 15 as shown in Figure 3, while rotation of the shaft 18 connected to the thermostat 16 varies the temperature at which current will be shut off in the circuit controlled by that 25 thermostat. Considering the thermostat 15 and its connecting shaft 17 as shown in Figure 1, the shaft 17 is connected for rotation by an adjusting knob 20. A similar adjusting knob 21 is provided for operating thermostat 16 through shaft 18. 30 Each of the adjusting knobs is provided with a projecting shaft 22, the shaft 22 for the knob 20 being shown in Figure 1. This projecting shaft 22 is of sufficient length that the knob 20 will be supported for rotation on the shaft 22 in a 35 suitable bearing block 23.

As is evident on inspection of Figure 1, the controls for operating the thermostats 15 and 16 made up of the knobs 20 and 21 and the connecting shafts 17 and 18 extend under a work table 25. The work table 25 is connected with the shoe 10 by means of brackets 26, 27 and 28. The bracket 26 is preferably welded to the brackets 27 and 28 and the aforesaid brackets 27 and 28 extend between the table and shoe 10. The purpose of the brackets 26, 27 and 28 is to secure the table 25 and shoe 10 together with the edge of the table 25 adjacent one edge of the shoe 10. For the purpose of retaining as much of the heat generated by the heating elements 13 and 14 as possible for transfer to the shoe 10, an insulating member 29 is provided which, as shown in Figures 1 and 3, extends under the shoe 10 and over the two loops 13 and 14 of the heating element. The insulating member 29 is secured 50 by contact with four projecting bosses, two of

which 31 and 32 are shown in Figure 3. These bosses are so located as to be in line with the connecting members 27 and 28 so that such connecting members 27 and 28 lying on the outside of the insulating member 29 may serve as connecting portions through which suitable screws may be placed to secure the members 27 and 28 to the shoe while holding the insulating member 29 between the ends of the members 27 and 28 which extend under the table 25 also extending over the ends of the bracket 26 and are secured to the table by means of screw fastenings as shown. It is apparent that adjustment is provided in the connection of the brackets 27 and 28 to the table 25. The bracket 26 extends between the ends of the brackets 27 and 28 and near the center of this bracket 26 suitable connections 33 and 34 are provided spaced apart to receive a support member 35 which, as shown in Figures 8 and 9, is positioned under the table 25. Another support member 36, shown in Figure 8, is adapted to contact and be connected with a supporting boss 37 under the shoe 10. Details of these supports and the actuation thereof is disclosed in co-pending patent application Serial Number 587,315 filed April 9, 1945, in the name of Arthur R. Constantine.

Referring particularly to Figures 1 and 3, it is seen that the table 25 may be assembled with the adjusting knobs 20 and 21 first put in position, the length of the shaft 22 on the knob being sufficient to support the knob entirely independent of any support from connecting shaft 17. The interior of the knob 20 which is similar to the knob 21 is provided with a spring 38 which is located on the axis of rotation of the knob 20 and the end of the shaft 17 is shaped as to fit into a slot 39 in the knob 20 adjacent the spring 38 and the opposite end of the shaft 17 fits into a slot 40 in a shaft 41 of the thermostat 15. Just above the knob 20 in the table 25 a display window 43 is provided so that the face of the knob 20 can be viewed through the table. Also adjacent the knob 20 is an electrical lamp bulb 44 provided for illumination of the knob 20 to provide better visibility through the window 43. A similar window 45 is also provided to give a view of the knob 21, and likewise illumination is provided by a second electric light bulb 46. The light bulbs 44 and 46 are in series with the heating elements 13 and 14 respectively as shown in Figure 4, so that when the circuit is broken to turn off the heat by the thermostatic switches, the lights 44 and 45 then are out. Therefore the illumination of the knobs 20 and 21 through the windows 43 and 45 indicates that the heat is on in the circuits 13 and 14. Suitable inscriptions may be placed on the knobs 20 and 21, which inscriptions may be seen by inspection through the transparent windows in the openings 43 and 44.

It is evident on inspection of Figure 1 that the knobs 20 and 21 are definitely positioned relative to the table 25 and the openings 43 and 44 above them by the fact that a shoulder 47 on the knob 20 contacts the end of the bearing 23. When it is desired to connect the table 25 to the shoe 10, the heating elements 13 and 14 of the shoe 10 together with the insulating member 29 are first assembled separately and the part underneath the table 25 including the knobs 20 and 21 are placed in position so that the connecting brackets 26, 27 and 28 can then be secured to the shoe 10. In order to connect the shoe 10 and table 25 these brackets can then be secured to the

table 25 which results in positioning the table 25 adjacent the edge of the shoe 10 as shown in Figure 3. The fact that the connecting elements for connecting the brackets 27 and 28 to the table 25 are capable of adjustment to push the table 25 toward and away from the end of the shoe 10 makes it possible to position the end of the table 25 adjacent the shoe 10 with suitable space between the shoe 10 and table 25 as shown in Figure 1 regardless of slight variations in different pieces due to manufacturing tolerances. However, even though there may be a variation in the position of the table 25 relative to the shoe 10, the position of the knobs 20 and 21 relative to the openings 43 is definitely determined by the table 10 and connecting shaft 17 which may then be inserted and put in place by pushing the end of the connecting shaft 17 into the slot 39 to push the spring 38 to nearly its maximum compression. The opposite end of the connecting shaft 17 may then be inserted in the slot 40 to complete the connection between the knob 20 and the thermostat 15 through its shaft 41. Because of the fact that the spring 38 is capable of immediate expansion connecting shaft 17 will be held in position with sufficient variation in length being allowed to make up for any variations in the distance between the connecting knob 20 and the thermostat 15. If the connecting knobs 20 and 21 were not made to be definitely positioned under the table 25 regardless of variation there would be a relative positioning of the knobs 21 and 22 under the openings 43 and 45 by the adjustment of the table relative to the shoe 10 so that the knobs 21 and 22 might not always be clearly visible through openings 43 and 45, while with the construction shown such change does not effect the position of the knobs 21 and 22 relative to the openings 43 and 45. After the assembly has been completed between the table 25 and the shoe 10, a connecting and shielding member 50 which covers all of the elements under the shoe 10 and table 25 to make a smooth under surface for the shoe and table unit is provided and is held in position by suitable group connections extending around the edges of the shoe and table. However, as shown in Figures 1, 7 and 8 the shielding member 50 is, of course, provided with openings 51 and 52 adjacent the knobs 20 and 21 in order that the knobs 20 and 21 may be manually rotated by the operator. By rotating the knobs 20 and 21 through openings 51 and 52 beneath the table 25 and by observing the setting inscribed on the knobs 20 and 21 through the windows 43 and 44 on the top of the table 25, the operator may set the thermostats 15 and 16 for any desired temperature.

It is apparent that the construction shown makes a single unit of the shoe 10 and table 25 satisfactorily connected together. It is also evident that the brackets 26, 27 and 28 provide a structural connection between the support 35 of the table and the shoe 10 and in effect provide two supports for the shoe 10 spaced on opposite sides of the central support 37, which support 37 as previously mentioned, connects with the vertical support 36.

Although the construction shown has been described in specific detail it is intended that various modifications may be made within the scope of the following claim.

I claim:

In an ironing machine shoe and table combination, a shoe, a table adjacent said shoe, connections between said shoe and said table per-

mitting adjustable movement of said table relative to said shoe, a heating element under said shoe, a thermostatic element adjacent said heating element for controlling said heating element, a rotatable control member for said thermostatic element located under said table for rotation and in a definite position relative to said table, a shaft connecting said thermostatic element with said rotatable control member, a slot in said rotatable control member to receive said shaft, and 10 a resilient member urging said shaft toward said thermostatic element whereby small variations in distance between said control member and said thermostatic element caused by adjustment of relative position of said shoe and table are 15

compensated without changing the position of said rotatable control member relative to said table.
